 New York, N. Y., a corporation of New York

Application January 20, 1944, Serial No. 518,985

8 Claims. (Cl. 234—5.8)

1

This invention relates to typewriting machines. A broad object of the present invention is to provide a typewriter suitable for use in the teaching of touch typewriting.

An object is to provide a typewriting machine which may be used to discover faults in typewriting, such as lack of rhythm in the operation of the keys of a typewriter.

An object is to provide a typewriting machine with means to show typists' faults graphically.

An object is to provide a means of tracing, in juxtaposition to the characters or spaces of a line of typewriting, graphic representations which enable the teacher of touch typewriting to detect erratic operation of the typewriter keys.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a perspective view showing the present invention attached to a standard typewriting machine;

Fig. 2 is a vertical section on the line 2—2 in Fig. 1;

Fig. 3 is a top view of the tracing means;

Fig. 4 is a front view of the tracing means;

Fig. 5 is a vertical section on the line 5—5 of Fig. 1;

Fig. 6 is a specimen showing the graphic representations which are produced by the device in juxtaposition to the printed characters.

The present invention has been shown in the drawings and will be described hereinafter as applied to the well known "Electromatic" typewriter, formerly known as the "International." It will be understood, however, that the invention is not restricted in its application to the typewriter shown, or even to a power operated typewriter, but may be applied to wholly manually operated typewriters, since the mode of attachment of the means for tracing graphic representations is simple and may be readily effected for any well known typewriting machine.

In Fig. 1 the typewriting machine base 10, the keys 11, the type bars 12, the front cover 13, and the platen 14 are shown. The type bars, as usual, are guided to the printing point by a type guide 15 (Figs. 1, 2 and 4) on the back of which is vertically slidably mounted the usual ribbon guide and vibrator 16. This ribbon vibrator is automatically raised each time a character is printed by the type bars 12 through suitable universal bar

2

mechanism not shown. However, in the well known "Electromatic," ordinarily the ribbon vibrator is not operated when the space bar 17 (Fig. 1) is used to space between words and other characters where spacing is required.

The means for tracing graphic representations is supported by the front cover 13 (Figs. 1 to 4) and is carried by a post 18 removably secured to the cover 13. Pivotedly mounted on the post 18, as by means of the rod 19, is an arm 20 which extends rearwardly of the post and to the left to a point close to the platen 14, as most clearly shown in Fig. 2. The arm 20 is formed with an extension or side arm 20a which has a hole loosely supporting a suitable pen 21 which conveniently may consist of an ordinary fountain pen.

The spring 22, anchored to a lug formed in the main part of the arm 20 and to a ring 23 slipped over the tapered end of the pen 21, tends to press the pen toward the platen. The nibs of the pen project into an inclined oval hole 24a (Fig. 4) of a lever 24 pivoted at 25 in a slot in the arm 20 located just above the printing point and approximately tangent to the platen as most clearly shown in Fig. 2. The lever 24 is urged in a clockwise direction (Fig. 4) by a spring 26 which is anchored to a lug formed in the extension arm 18a of the post 18. The spring 26 also urges the arm 20 in a clockwise direction (Fig. 3) into engagement with a stop screw 27 carried by a second extension arm 18b of the post 18. The stop screw 27 is adjusted so that the arm 20 and lever 24 adjacent the platen is clear of a sheet 28 (Fig. 2) wrapped around the platen.

On account of the fact that the usual paper bail cannot be used, the end of the arm 20 adjacent the platen is formed with a concave cylindrical surface 20b which is concentric with the axis of the platen 14 and acts as a guide to hold the sheet

28 wrapped around the platen. The arm 20 is also somewhat triangular shape at its end when viewed in plan, as best shown in Fig. 3 at 20c, to guide the edges of the sheet 28 underneath the end of the arm in the event the carriage is moved

a little too far to right or left so that the edges of the sheet 28 parallel with the line of feed pass the printing point on either side and bulge away from the platen. The right hand wall of the slot in the arm 20 receiving the lever 24 acts as a stop

to restrict clockwise movement of lever 24, as most clearly shown in Fig. 4. The arm of lever 24 having the hole 24a extends downwardly so that the nibs of the pen 21 normally occupy a position a little above the printing point with the edge of the lever 24 just clear of the type elements when

in printing position to prevent said elements from striking said lever.

A little to the right of the printing point, the lever 24 is formed with a shoe 24b which extends radially away from the axis of the platen to a point just over and in the path of the ribbon vibrator 16 in which is guided the usual inking ribbon 29. Each time a type bar is operated, the ribbon vibrator 16 is raised simultaneously with the movement of the type bar to the printing position and in its movement upwardly the ribbon vibrator engages the shoe 24b and rocks the lever 24 in a counterclockwise direction against the tension of spring 26. This causes the pen 21 to trace an inclined loop 21a (Fig. 6), over every character printed but no such loop is traced when the space bar is operated since the ribbon vibrator, as aforesaid, does not operate except when a character is printed.

It will be understood that the machine is equipped with the usual carriage feeding power spring and carriage return mechanism. The escapement mechanism is removed or released in some convenient way as by tying down the usual carriage release levers.

Means is provided to compel the carriage feeding spring to feed the carriage at a uniform rate of speed instead of intermittently as would be the case ordinarily with the escapement mechanism in use. This means is shown in Figs. 1 and 5 and includes a rack 30 which is preferably removably attached at its left hand end (Fig. 1) to the right hand side plate of the carriage. The rack 30 is preferably formed of an angle strip along one edge of which the teeth 30a are cut which mesh with a pinion 31 (Fig. 5) on a pin 32.

The pin 32 is pressed into a horizontal hole in a block 33 secured to a plate 34 which may be fastened in any suitable manner to the surface of the desk or table supporting the typewriting machine or may form part of a plate or bracket secured in some suitable fashion to the base 10 of the machine. The upper end of block 33 is cut with a horizontal rectangular slot 33a (Figs. 1 and 5) which receives a block 35 slotted to accommodate the rack 30 and also formed with a cylindrical space 35a to accommodate the pinion 31. The pin 32 also extends through a hole in the block 35 registering with the hole in the block 33 carrying the pin 32, as clearly shown in Fig. 5. A slot in the block 35 accommodating the rack 30 and the bottom wall of the slot 33a in the block 33 act as a guide for the rack 30.

Loosely mounted on the pin 32, between the pinion 31 and the collar 36 on the pin 32 is a pulley 37. This pulley 37 is connected by a belt 38 to a suitable driving motor M of the adjustable speed, constant speed type having suitable reduction gearing, in which means is provided for enabling the operator to adjust the speed to any desired value. This motor tends to drive the pulley 37 in the direction of the arrow (Fig. 1), that is, in the same direction as the pinion 31 will be turned when the typewriting machine is moved in a letter spacing direction by the power spring.

The pinion 31 is formed from a bushing or sleeve which extends externally of the blocks 33 and 35 through a suitable bore or opening 34b large enough to accommodate the pinion 31 and has wrapped around it a coil spring 39, one end of which extends radially of the pin 32 and is hooked around a stud 37a carried by the pulley 37.

Preferably, the spring 39 is coiled a trifle smaller than the shank of the pinion 31 and

pressed on the shank so that when the pinion 31 is rotated with the carriage travelling in letter spacing direction, the shank of the pinion tends to wrap the spring 39 more tightly around the shank of the pinion and thereby tends to turn the pulley 37 through pin 37a. When the carriage is returned, however, the pinion 31 rotates in the reverse direction and tends to loosen the spring 39 allowing the shank of the pinion to turn loosely. In other words, the spring 39 acts as an overrunning clutch connection between the pinion 31 and the pulley 37. The effect of this construction is that when the motor is driving the pulley 37 at a speed lower than the pinion 31 tends to rotate while the carriage is letter spacing, the spring 39 acts as a restraining means and prevents the pinion from being rotated faster than the pulley 37 is driven by the motor whereby the driving connections shown in Fig. 5 act as a brake and prevent the carriage from travelling faster in letter spacing direction than a predetermined rate depending upon the speed adjustment of the motor.

When the carriage is returned in the usual way, rack 30 is thrust to the right (Fig. 1), or rearwardly of the plane of Fig. 5, and the shank of pinion 31 rotates idly in the coiled part of spring 39, and little obstruction is offered to the returning carriage, except by the tension of the power spring.

Pulley 37 is turned slowly by the motor but the power spring tends to drive the pulley faster than the motor. The power spring, however, is not powerful enough to drive pulley 37 faster than the motor since the mechanical advantage of the belt drive and the reduction gearing forming part of the motor is one of speed rather than force, considering the power spring as the actual driving means and the driving motor and the parts shown in Fig. 5 may be regarded as functioning like a centrifugally actuated brake having means to adjust the brake manually to regulate the speed of the carriage.

It is quite clear that by suitably adjusting the speed of the motor the speed of carriage may be adjusted to the capabilities of the operator.

At the end of each line the carriage is returned and the platen line spaced in the usual way, the line spacing operation taking place first. This causes the pen 21 to trace a line 40 (Fig. 6) joining the end of one line to the end of the next line and extending almost vertically downwardly. When the carriage returns a horizontal line 41 is traced which conveniently serves as a reference or base line along which time intervals between characters may be measured with a suitable scale if necessary. Of course, after returning the carriage, the operator proceeds to type and for each character printed a loop 21a is formed directly above the printed character and starts from the base line 41 traced during the preceding carriage return operation and returns to said line.

If the keys are operated with an even rhythm, as in the case of the keys for the first three letters of the word "DIVER" in the top line of Fig. 6, the loops 21a will all be uniform in height, shape, and spacing, and will start and finish on base line 41. If the operator hesitates too much or is too slow in operating two successive keys, the loops 21a will be spaced further apart as at point 21b. At this point, the operator has been too slow in operating the "E" key with the result that the pen has retraced part of its path along the base line 41 for a distance almost half the

length of the part of the base line associated with the loop formed in writing the letter "V." On the other hand, if the operator actuates some keys too fast the printing cycles will overlap and produce the effect shown at 21e (Fig. 6) which arose from too hasty operation of the "I" key in printing the word "DIRTY" on the first line. When the space bar is operated, the pen 21 is not actuated but retraces the base line 41 for a distance which will depend upon the gap in time between completion of the operation of the type bar for the last letter of a word and the beginning of the operation of a type bar for the first letter of a new word as indicated at 21d in Fig. 6. Here the length of the gap measured along the base line 41 as compared with similar gaps will indicate lack of rhythm in operating the space bar.

When an even rhythm is reached, the gaps 21d should be of uniform lengths and the loops 21a should all be nearly uniform in shape, spacing, height, and distance apart.

In the case of a power operated typewriter such as the one disclosed, each type bar has a definite operating time for each cycle and with a properly adjusted machine the operating cycles are approximately equal for all type bars for each speed adjustment of the machine, such machines usually being provided with a means to adjust the force of the blow of the type bars by adjusting the speed of the driving motor. Thus each of the loops 21a should be substantially identical in shape for all type bars and, when a condition like that shown in 21c is observed, it indicates that the type bars are overlapping in their cycles to an extent which may cause collision between a restoring type bar and one on its printing stroke. When the loops are evenly spaced, as in printing the letters "DIV" of "DIVER" in the top line of Fig. 6 it indicates that the operator is closely following the capacity of the machine to print without overlapping the cycles of operation of the type bars to an extent to cause erratic spacing of the characters. This frequently is a difficulty of beginners particularly in learning to operate manual typewriters because of the fact that some key combinations are much easier for some operators than others on account of varying degrees of dexterity of the fingers, left handedness, etc.

In the normal operation of a standard typewriter, where the carriage feeds only when a type bar is operated, the fault of rhythm consisting of too much time elapsing between successive impressions will not be evident since the carriage will space and stop between letters and it is immaterial how long the operator delays depressing the next key so far as the appearance of the work sheet is concerned. A fault of this kind is quite difficult to detect in a fast operator, even with very close observation of the fingers.

The opposite fault of rhythm, on the other hand, shown at 21e (Fig. 6), is very easy to detect, particularly with power operated typewriters, because it causes overprinting of characters or too close spacing on the left hand side and not enough on the right hand side of the second of three successive characters. However, the loops or graphic representations 21a, being very uniform in shape and size as compared with letters having varying widths, shapes, and sizes, are a better means of determining how bad the second fault of rhythm may be in each case.

The printing of the characters below the graphic representations shows clearly which key combinations are difficult for a particular oper-

ator and show which fingers require special key exercises to cure the faults. Even without the printed characters, however, the invention is still useful since the printed characters are needed only to localize the faults of rhythm in the operator's fingers by reference to the keyboard.

In the machine of the type disclosed, the universal bar which actuates the ribbon vibrator, as in most commercial machines, begins to move 10 the ribbon vibrator when the type bar starts toward the printing point so that the ribbon vibrator, and hence the pen 21, travel at a rate proportional to the velocity of the type bar. Thus the loops 21a are also graphical representations 15 of the operating cycles of the type bars and it is possible to detect faulty type bar operation by comparing the shapes of the loops made by different type bars, particularly with the ones known to be striking properly.

20 While the pen 21 is shown as actuated by the ribbon vibrator as a preferred form involving the least alteration of the machine, it will be understood, that any suitable means for actuating automatically the means for producing graphic 25 representations of the characters are contemplated as within the scope of the claims.

While there have been shown and described 30 and pointed out the fundamental novel features of the invention as applied to a single embodiment it will be understood that various omissions and substitutions and changes in the form and 35 details of the device illustrated and in its operation may be made by those skilled in the art, without departing from the spirit of the invention. It is the intention, therefore, to be limited only as indicated by the scope of the following claims.

What is claimed is:

1. In a typewriting machine, in combination 40 with the platen; means for typing a line of characters on a work sheet on the platen, a ribbon vibrator, means to feed the platen in a letter-spacing direction and at a constant rate of speed while the typing means is typing a line of characters on said work sheet; and means actuated by the ribbon vibrator for tracing directly above each character in said line a curve forming a graphic representation, said representations by 45 their shapes, spacing, and distances apart indicating faults in typing.

2. A typewriting machine having a platen, means for typing a line of characters on a work sheet on said platen, means to cause the platen to feed in a letter spacing direction at a controlled and uniform rate of speed while said line is being typed; and means controlled concomitantly with the typing of said characters for tracing a line of graphic representations, said representations by their shape and spacing marking the typist's rhythm in juxtaposition with the 50 typed line.

3. In combination with the platen, carriage, and typing means of a typewriting machine; a tracing pen disposed in front of the platen so as to trace above each character typed on a record sheet carried by said platen a representation, means controlled concomitantly for actuating said tracing pen each time a character is typed, and means to feed the carriage at a uniform rate to enable the spacing of the representations to denote the rhythm of the typist in writing a line of characters.

4. In combination with the platen, carriage, and typing means of a typewriting machine; a record sheet support, means controlled concom-

itantly with the typing means in typing a line of characters on the record sheet carried by said support to trace on said sheet a line of representations, and means to feed the record sheet support to space said representations and characters apart in proportion to the elapsed time between impressions.

5. In combination with the carriage of a type-writing machine; means to type a line of characters on a record sheet on the carriage; and means controlled concomitantly with the printing of each character to trace on said record sheet, a graphical representation in juxtaposition with the latter, said tracing means being operative to trace a base line for said representations when said carriage is returned at the end of a line.

6. In combination with the carriage of a type-writing machine, means to type a line of characters on a work sheet on the carriage, a ribbon vibrator; and means actuated by the ribbon vibrator for tracing above each character printed a graphical representation and operative when the carriage is returned to trace a base line for the graphical representations on the next line to be typed.

7. In combination with the carriage of a type-writing machine, means to print characters on a work sheet carried by said carriage, a ribbon vibrator, means to feed the carriage in a letter spacing direction at a uniform rate of speed 30 while said characters are being printed, and a tracing pen mounted independently of the carriage and having its point coacting with the record sheet and actuated by said ribbon vibrator

to trace graphical representations in juxtaposition to said characters, said pen remaining immovable while the carriage is returned so as to trace a base line for said representations.

8. In combination with character typing means: means for making a graphic representation, including a tracing pen adjacent the typing point, a record sheet support, means controlled concomitantly with said character typing means to move said pen in one direction, and means to effect a relative movement between the pen and a record sheet on said support at an angle to the first direction while typing the characters on said record sheet, said movements coacting to trace a curve on said sheet in juxtaposition to each character.
